CLAIM

The ornamental design for a packaging system, as shown and described.

DESCRIPTION

FIG. 1 is an exploded perspective view of a package system showing my new design;

FIG. 2 is an exploded perspective view of an insert package; with the book removed from it;

FIG. 3 is a front perspective view of the book;

FIG. 4 is a rear perspective view of the book; and,

FIG. 5 is a side perspective view of the book; shown in an open position.

The insert package and book are shown separately for clarity.
